UNITED STATES PATENT OFFICE.

GEORGE T. PEARSONS, OF NEW YORK, N. Y.

FIRE-EXTINGUISHER.

1,400,906.

Specification of Letters Patent. Patented Dec. 20, 1921.

Application filed April 12, 1917, Serial No. 161,897. Renewed May 3, 1921. Serial No. 466,583.

To all whom it may concern:

Be it known that I, GEORGE T. PEARSONS, a citizen of the United States, and a resident of the borough of Manhattan, in the city, 5 county, and State of New York, have invented certain new and useful Improvements in Fire-Extinguishers, of which the following is a specification.

This invention relates to fire extinguishers

10 in which a fire extinguishing liquid is ejected from a reservoir, the fire extinguishing liquid being of such a character as to volatilize as it comes in contact with or adjacent the heat of a fire and thereby forming a gas blanket to 15 exclude the oxygen from the fire and smother the same, and it is the primary object of the invention to improve the general construction of fire extinguishers of this character to increase the efficiency thereof.

20 A further object is to provide a fire extinguisher in which the fire extinguishing liquid comprises a highly evaporable liquid, such as carbon tetrachlorid or a carbon tetrachlorid compound.

25 In the commercial use of fire extinguishers of this character it is required that the outlet of the reservoir be maintained open, or the contents of the reservoir of the extinguisher be open to the atmosphere, with the result 30 that the fire extinguishing liquid quickly evaporates, and when it is desired to use the extinguisher the fire extinguishing liquid has evaporated or deteriorated and the extinguisher is useless. It is a further object of 35 the invention to provide means to seal the fire extinguishing liquid from the outlet.

40 It is another object of the invention to provide a fire extinguisher of this character in which the fire extinguishing liquid is ejected from the reservoir by a pressure created within the reservoir.

45 Another object of the invention is to provide a gas generator in which gas generating materials are carried therein in a separated condition and open to each other but prevented from uniting or mixing in the normal upright position of the generator and are adapted to unite and mix and generate gas when inverted.

50 Another object of the invention is to provide a fire extinguisher in which the gas generator is placed in the fire extinguishing liquid, and the outlet of the generator provided with means to seal the same by the fire extinguishing liquid in the reservoir.

55 Another object of the invention is to pro-

vide an extinguisher which is set in operation by inverting the same, and to provide means to pivotally support the extinguisher and maintain it in upright position, said means 30 including fusible means to release the extinguisher and permit it to assume an inverted position.

Other objects and advantages will herein-after appear.

65 In the drawing accompanying and forming a part of this specification Figure 1 is a sectional side elevation of a fire extinguisher showing an embodiment of my invention, the section being taken on the line X—X of Fig. 70 2 and looking in the direction of the arrows; and

Fig. 2 is a plan view.

Similar characters of reference designate like parts throughout the different views of 75 the drawing.

In the embodiment of my invention shown in the drawing there is provided a reservoir to contain a fire extinguishing liquid comprising a cylindrical body portion 3 having 80 a closed bottom 4 and a head 5 having an opening closed by a removable cap 7. Trunnions 8, 9 extend laterally from the reservoir adjacent the one end, shown as the bottom, the axis of said trunnions being offset with 85 relation to the longitudinal axis of the reservoir, as shown in Fig. 2 and for a purpose to be hereinafter described. The trunnions 8 and 9 are journaled in supports 10, 10 to pivotally carry the extinguisher. The outlet 90 of the reservoir in the present instance is in one of the supporting trunnions, as 8, for which purpose said trunnion is constructed in the form of a nozzle, as at 11.

The fire extinguishing liquid is adapted to 95 be ejected from the reservoir by pressure within the reservoir, such for instance as carbonic acid gas pressure generated by means within the reservoir and operable by the inverting of the same. I have shown a type 100 of generator substantially as disclosed in my co-pending application filed November 27, 1916, Serial No. 133,521 comprising a receptacle 12 open at one end and having an outlet in the closed end with a tube 13 se- 105 cured in the outlet and extending into the receptacle, the bore of the tube constituting a continuation of the outlet and having lateral ports 14. A second receptacle 15 having one end open, which is in the nature 110 of a cover, is adapted to have telescoping connection over the open end of the re-

ceptacle 12, and the open end co-operates with a flange 16 at the bottom of the receptacle 12 to provide an entirely closed receptacle. Engaging in the first receptacle 5 is a third receptacle 17 having an open end and of less diameter than the receptacle 12 to provide a space between the walls of said receptacles, said third receptacle being supported upon the outlet tube 13 and 10 thereby providing a space between the bottoms of the two receptacles. This receptacle is adapted to contain an alkali, such as bicarbonate of soda, to constitute one of the gas generating materials, and carries an 15 other receptacle 18 in the form of a glass bottle having another gas generating material, such as sulfuric or hydrochloric acid, free from the other gas generating material in the normal position of the extinguisher. 20 The bottle 18 is closed by a stopper 19 having an outlet tube or tubes 20 and a projection 21 to engage with the end of the receptacle 15 to maintain the bottle within the third receptacle and the latter in position 25 against the outlet tube 13. By this construction there is provided a generator in which the gas generating materials are held in a separated condition and at all times open to each other but prevented from unit- 30 ing in the normal upright position of the generator and adapted to unite when the generator is inverted. The tubes 20 extend to adjacent or above the top of the receptacle 17 and as the extinguisher is inverted the 35 acid will flow through said tubes to unite with the bicarbonate of soda in the receptacle 17 at a point below the surface thereof. To filter and render the gas anhydrous or dry and non-acid there is provided a material 40 in the space between the receptacles 12 and 17 through which the generated gas passes to absorb any particles of acid which may be thrown off with the generated gas, sodium carbonate having been found to answer the 45 purpose. The outlet of the generator through the tube 23 is at all times open to the reservoir, and as the generator is placed and immersed in the liquid in the reservoir the liquid serves to hermetically seal the 50 generator and prevent deterioration of the gas generating materials.

The generator is carried in the reservoir in a tubular carrier 22 secured to the bottom of the reservoir, and the generator being an 55 integral unit it may be removed for the purpose of re-charging, cleaning or the substitution of another generator.

As stated the fire extinguishing liquid is carbon tetrachlorid or a carbon tetrachlorid compound which is of a highly evaporable or very volatile when exposed to the atmosphere, and as it is essential that the outlet of the reservoir be at all times open to the atmosphere means are provided to 60 seal the fire extinguishing liquid from the

atmosphere through the outlet. This sealing means comprises a liquid or fluid which is non-evaporable, or has a low evaporation, when exposed to the atmosphere, and is interposed between the fire extinguishing 70 liquid and the outlet. As shown in the drawing the extinguisher is set in operation by inverting and to seal the fire extinguishing liquid from the outlet a tube 23 is connected to the outlet to constitute a continuation 75 thereof and extending to adjacent one end or the top of the reservoir with its open end above the level of the fire extinguishing liquid, as shown in a general way by C. This tube 23 which is movable with the reservoir 80 also serves to connect the outlet with the liquid adjacent the bottom of the reservoir and shut off the expelling gas pressure from the outlet during the ejecting of the fire extinguishing liquid. The sealing liquid 85 shown at S is of less specific gravity than the fire extinguishing liquid and will float on the surface thereof, and the level of said sealing liquid is below the inlet to the outlet tube 23. In the use of an extinguisher of 90 the invertible type glycerin has been found to satisfactorily answer the purpose of sealing as when the extinguisher is inverted it will quickly pass through the fire extinguishing liquid and assume a position on 95 the surface of said liquid, and thereby is prevented, or the greater part thereof, from being expelled previous to the fire extinguishing liquid. To prevent the expelling of 100 said sealing liquid after the fire extinguishing liquid has been expelled from the reservoir, there is a space left between the end of the reservoir and the inlet to the tube 23 sufficient to accommodate the sealing liquid and permit the expelling of the gas. 105

By locating the supporting trunnions 9 adjacent the bottom and at one side of the longitudinal axis of the reservoir the extinguisher tends to always assume an inverted position. Suitable means are provided to releasably retain the extinguisher in upright position, and shown as a cable or chain 24 secured at one end, as at 25, to the cover 7 and passing over a pulley 26 with the opposite end caught onto a hook 27, which may be at a place remote from the extinguisher. The extinguisher illustrated is for use in connection with tanks or vats containing highly combustible material, such as oil, and to be supported with the discharge nozzle 11 above the top of the tank, whereby as 110 the extinguisher is set in operation the fire extinguishing liquid will be discharged directly over the top of the tank. To automatically set the extinguisher in operation 115 when a fire occurs the cable 24 has a link 28 of material fusible at a low temperature, and upon the fusing of which link the extinguisher will be released and permitted 120 to assume an inverted position. To maintain 125 130

the cable sustained so as not to interfere with the inverting movement thereof the fusible means 28 is utilized to connect portions of the cable and provide an integral slack portion or loop 29 which will be of sufficient length to permit the extinguisher to assume an inverted position.

In operation the charged generator is placed in the carrier 22 when the fire extinguishing liquid is supplied to the reservoir and the cover 7 secured in place. When the extinguisher is inverted to utilize the same the acid will flow from the receptacle 18 through the tubes 20, and due to the length of the tubes will unite with the bicarbonate of soda at a point below the top of the soda. The gas generated by the mixing of the acid and soda passes between the walls of the receptacles 12 and 17 through the filtering material below the receptacle 12 and through the lateral ports 14 and through tube 13 into the reservoir where its force is exerted on the fire extinguishing liquid to discharge the same. As the extinguisher is inverted the generator will drop against the top, then the bottom, of the reservoir. To maintain the generator in an inverted position the carrier 22 and the generator are made of such length so that a portion of the generator will at all times engage in the carrier. As the extinguisher is inverted the sealing liquid S will immediately and quickly pass through the fire extinguishing liquid to assume a position on the top thereof, whereby as the expelling force of the gas becomes sufficient to expel the contents of the reservoir the fire extinguishing liquid will be adjacent the bottom and be expelled.

Having thus described my invention, I claim:

1. In a fire extinguisher, the combination of a reservoir to contain fire extinguishing liquid; an outlet for the reservoir; a liquid seal between the outlet of the reservoir and fire extinguishing liquid; and a gas generator in the reservoir having an outlet open to the reservoir, said generator being arranged to carry gas generating materials in a separated condition and open to each other in the normal upright position of the extinguisher and adapted to be sealed by immersion in the liquid in the reservoir.

2. In a fire extinguisher, the combination of a pivotally supported reservoir; an evaporable fire extinguishing liquid in said reservoir; an outlet for the reservoir through the pivotal support of the reservoir leading from one end and the top of the extinguisher in the normal position thereof to at all times maintain the interior of the reservoir open to the atmosphere; a non-evaporable liquid of less specific gravity than the fire extinguishing liquid to float upon the surface of the fire extinguishing liquid and seal the fire extinguishing liquid from the atmosphere through the outlet in the normal upright position of the extinguisher; fusible means to retain the extinguisher in upright position and the fusing of said means permitting the extinguisher to assume an inverted position; and a gas generator in the reservoir to generate gas and place the fire extinguishing liquid under compression when the extinguisher is inverted for the purpose specified.

3. In a fire extinguisher, the combination of a pivotally supported reservoir to contain fire extinguishing liquid and having an outlet to at all times maintain the interior of the reservoir open to the atmosphere; a liquid to seal the fire extinguishing liquid from the atmosphere through the reservoir outlet in the normal upright position of the extinguisher; means to retain the extinguisher in upright position adapted to automatically release the extinguisher and permit it to assume an inverted position when the temperature reaches a predetermined degree; and a gas generator immersed in the liquid in the reservoir having an outlet open to the reservoir, said generator being arranged to carry gas generating materials at all times open to each other but prevented from uniting in the normal upright position of the extinguisher and adapted to unite and generate gas when the extinguisher is inverted to place the liquid in the reservoir under compression for the purpose specified.

Signed at New York city, in the county of New York and State of New York, this 9th day of April, 1917.

GEO. T. PEARSONS.
